UNITED STATES PATENT OFFICE.

WILLIAM U. GRIFFITHS, OF PHILADELPHIA, PENNSYLVANIA.

FLUSH-TANK FOR WATER-CLOSET APPARATUS.

1,142,250.

Specification of Letters Patent.

Patented June 8, 1915.

Application filed August 23, 1913. Serial No. 786,232.

To all whom it may concern:

Be it known that I, WILLIAM U. GRIFFITHS, a citizen of the United States, and a resident of Philadelphia, in the county of 5 Philadelphia and State of Pennsylvania, have invented certain new and useful Improvements in Flush-Tanks for Water-Closet Apparatus, of which the following is a specification.

10 My invention relates to improvements in flush tanks for flushing water closet hoppers and the like, and it has for its object to provide an improved construction of means for starting the siphonic action of a siphon situated in the flush tank.

15 A further object of my invention is to provide a construction which is simple and therefore may be economically manufactured, and one which also is efficient and 20 positive in its action.

25 In the accompanying drawing I have illustrated one form of a convenient embodiment of my invention, but it will be understood that changes in the details of construction may be made within the scope of 30 the claim without departing from the same.

35 In the drawing I have shown a water closet apparatus embodying my invention, the flush tank and a portion of the adjacent 40 mechanism being shown in vertical longitudinal section, while the water closet bowl or hopper and other associated mechanism are shown in side elevation.

45 Referring to the drawing, 1 designates a water closet hopper or bowl and 2 a valve mechanism for controlling the flow of water from the source of supply through a pipe 3 to the flush tank 4. The valve mechanism is controlled by means of a vertical rod 5 operated by the seat 6 when the latter is depressed. The seat is normally held in raised 50 position, as shown in the drawings, by means of a weighted arm or lever 7, the rear end of which is adapted to bear against and raise

55 or lift a vertical rod 8 when the seat is depressed downwardly upon the upper edge of the water closet bowl. The rod 8 is guided in its vertical movements in a well known manner. The upper end of the rod 8 projects into a chamber 9 formed at the lower end of the long leg of a siphon 10. The siphon is situated in the flush tank 4 in the usual and known manner.

60 11 designates a chamber or receptacle 55 which is situated in the chamber 9 and is

secured in position by means of screws 12, one only of which is shown, which engage a flange 13 formed upon the siphon structure. The screws 12 extend through flanges 14 upon the outer edge of the receptacle or 60 chamber 11. The bottom of the receptacle or chamber is provided with an opening 14, while the top is provided with an opening 15. The opening 14 is adapted to be closed by means of a disk valve 16 while the opening 15 is adapted to be closed by a disk valve 17. The two valves are connected together by means of a rod 18, so that when one of the said valves is moved, the other is moved in unison therewith.

70 The operation may be described as follows: When the seat 6 is depressed, it contacts with the upper end of the rod 5 to position the valves in the mechanism 2 so as to permit water to flow into the tank 4 and fill the same. At the same time, the rod 8 is moved upwardly, its upper end contacting with the valve 16 to cause the same to close the opening 14. Simultaneously, the opening 15 is opened. Consequently when 75 the water has reached a level in the tank which is above the plane of the top of the receptacle or chamber 11, water flows into the latter through the opening 15 to fill the same. When the seat 6 returns to the position illustrated in the drawing, the rod 8 drops down into the position also illustrated in the said drawing, permitting the valve 16 to open the opening 14, and simultaneously closing the opening 15. The water which 80 has been collected in the receptacle or chamber 11 flows out through the opening 14. The quantity of water in the receptacle or chamber 11 is sufficient to start siphonic action. The result is that the water is discharged from the flush tank through the siphon 10 and the flush tank pipe 20 into the water closet hopper or bowl, in the usual 85 manner, to flush and cleanse the same.

90 I claim:—

95 In a flushing apparatus for water closets, the combination of a siphon having an enlarged portion constituting a part of its longer leg, said siphon being situated in a flush tank, a receptacle situated in the enlarged portion of the said siphon, the top and bottom of the said receptacle each having an opening therethrough, the opening in the top communicating with the flush tank and the opening in the bottom communi- 100

110

cating with the longer leg of said siphon, valves for closing the said openings, means extending through the said receptacle and connecting the said valves together, and
5 means for operating said valves to close one of the said openings and simultaneously open the other for the purpose stated.

In testimony that I claim the foregoing as my invention, I have hereunto signed my name this 20th day of August, A. D. 1913.

WILLIAM U. GRIFFITHS.

In the presence of—

Wm. HARRISON SMITH,
CARRIE E. KLEINFELDER.
